UNITED STATES PATENT OFFICE.

CHARLES PATTEN, OF FAIRFAX, SOUTH DAKOTA.

GATE.

No. 849,351.

Specification of Letters Patent.

Patented April 2, 1907.

Application filed September 29, 1906. Serial No. 336,719.

To all whom it may concern:

Be it known that I, CHARLES PATTEN, a citizen of the United States of America, residing at Fairfax, in the county of Gregory 5 and State of South Dakota, have invented new and useful Improvements in Gates, of which the following is a specification.

This invention relates to improvements in gates, and more particularly to gates of the 10 swinging type designed for farm and similar use, the main object of the invention being to provide a gate of simple construction which is adapted to be economically manufactured in such a manner as to require the use of but 15 a small quantity of wood, thereby rendering the gate of value in those sections where lumber is scarce and posts difficult to procure and high-priced.

Another object of the invention is to provide 20 a gate of this character which is light in weight and offers but little surface for the action of the wind, which is strong, durable, and susceptible of being hung upon light posts, which can be easily opened and closed 25 by a child, pedestrian, or equestrian, which will swing open to the full extent in either direction, which will prevent the accumulation of resisting bodies of snow which usually drift and bank against heavy wooden gates, 30 and which when closed will be firmly and securely fastened in position and will strengthen the fence structure.

In the accompanying drawings, Figure 1 is a view in elevation, showing the gate in its 35 closed position. Fig. 2 is a similar view showing the latch-bar in released position. Fig. 3 is a view similar to Fig. 1, disclosing a modification in the construction of the gate. Fig. 4 is a perspective view of the latch-bar 40 and latch mechanism thereon. Fig. 5 is a perspective view of the guide for the upper end of said bar. Fig. 6 is a similar view of the keeper.

Referring to the drawings, 1 and 2 respectively designate the hinging and latch posts of the gate, and 3 and 4 braces and line wires of the fence structure secured thereto.

The frame of the gate comprises a hinging-stile 5, a top bar 6, secured at one end there- 50 to, and an inclined brace or strut bar 7, secured at its lower end to the lower end of the stile 5 and at its upper end to the top bar at a point about midway of the length of the latter. Strap-hinges 8 are secured to the frame 55 in such a manner as to strengthen and reinforce the stile and bars at their points of con-

nection and engage the post 1 to mount the gate for swinging movement thereon. A pin or other suitable support 9 may be fixed to the hinging-post and extend under one of the 60 hinges 8 to hold the gate-frame from downward movement on said post.

At the swinging end of the gate is a latch stile or bar 10, which is pivotally connected at its lower end to a bracket 11, arranged 65 upon the free end of a supporting-bar 12, pivotally connected at its inner end, as by a link 13, to the brace or strut 7, which latter is provided with a stop or abutment 14 to stay and limit the upward-swinging movement of 70 said bar.

The latch-bar 10 projects upwardly through a guide loop or strap 15, secured to the free end of the bar 1, and is free to slide in said guide in a direction longitudinally of 75 the gate. The gate structure is completed by one or more body-strands 16 of barbed or other wire suitably connected at their ends with the hinging stile and latch-bar.

The lower end of the latch-bar is adapted 80 to fit down into a keeper arranged at the lower end of the latch-post 2, said keeper preferably comprising a looped metallic strap 17, fastened at the free ends of its arms to the latch-post and provided at its outer 85 or closed end with an anchor member 18, adapted to be embedded in the ground. An operating handle or lever 19 is hinged or pivoted at one end, as indicated at 20, to the bar 10 and is operatively connected with a latch 90 member 21, consisting of a metallic loop or bail adapted to embrace the upper end of the post 2 and pivoted at the free end of its arms, as indicated at 22, to the lever 19. The pivot 22 is arranged below and in rear of the 95 lever-fulcrum 20, so that when the lever is turned down to a substantially horizontal position, as shown in Fig. 1, the latch-loop will be drawn upon to bind against the post 2, and thereby lock the bar 10 from upward 100 movement, while an upward movement of the lever to release position will slacken the latch-loop and permit it to be swung out of engagement with the post.

The supporting-bar 12 is connected at its 105 free end with the free end of the top bar 6 by a spring 23, which operates to stay and support said bar and draw the same upwardly to elevate and retract the latch-bar when the latch member 21 is released from engagement 110 with the latch-post. A barbed guard-wire 24 is connected at one end with the upper

end of the stile 5 and engages a short post 25, projecting upwardly from the bar 6, and projects beyond the same and is secured at its opposite end to said bar in rear of the lever 19. This wire acts as a truss to stay the bar 6, as well as a guard to prevent horses and cattle from pressing against and bearing down upon the top of the gate.

By reference to Fig. 1 it will be seen that when the gate is closed and locked the lower end of the bar 10 is inserted in the keeper 17, while the upper end thereof is fastened to the post 2 by the latch-loop 15, whereby said latch-bar is held in locking position with the spring 23 expanded. When the free end of the lever is thrown upward, the pivot 22 will shift upwardly and forwardly, thereby throwing the latch-loop out of engagement with the post and allowing the spring 23 to lift the bar 12 and latch-bar 10, whereby the latter will be moved upwardly out of engagement with the keeper 17 and may swing back in the guide 15, allowing the gate to be swung open in either direction. When the gate is again closed, the bar 10 may be forced downward into engagement with the keeper and the latch-loop again engaged with the post in an obvious manner to lock the gate.

It will be apparent from the foregoing description that the invention provides a gate which is light in weight, strong and durable in construction, and obviates the necessity of employing large posts or lengthy boards, thus producing a gate which may be economically manufactured in sections where lumber is scarce. Furthermore, the open structure of the gate avoids objectionable strain thereon from wind-pressure and prevents the accumulation of banks of drifted snow which would prevent the gate from having free movement, while the latch mechanism is of such a character as to be readily manipulated by a child, pedestrian, or equestrian.

In the modification disclosed in Fig. 3 the structure is the same in all material respects as that shown in Figs. 1 and 2 except that the supporting-bar 12^a extends the full length of the bottom of the gate and is connected by a rod 12^b with the lower end of the spring, while the lower portion of the gate-body is closed by a netting 12^c, of woven wire or other suitable material, fastened at its ends and lower edge, respectively, to the hinging-stile, latch-bar, and supporting-bar. This structure closes the lower portion of the gate without materially adding weight thereto to prevent hogs and other animals from passing beneath and escaping through the gate. Owing to its flexible nature, the screen moves freely with the supporting and latch bars, and consequently does not interfere with their operation.

Having thus described the invention, what is claimed as new is—

1. A swinging gate comprising a frame, a pivoted supporting-bar carried thereby, a latch-bar pivoted to the supporting-bar and in guided connection with the frame, a spring supporting the supporting-bar from the frame and operative to retract the latch-bar, and means for securing the latch-bar in latching position against the action of said spring.

2. A swinging gate comprising a frame, a latch-bar at the free end thereof in guided connection at its upper end with said frame, a supporting-bar pivoted at one end to the frame and at its opposite end to the lower end of the latch-bar, a retracting-spring connecting said supporting-bar to the frame, and latch mechanism carried by the upper end of the latch-bar to engage the latch-post and hold said latch-bar against retraction.

3. A swinging gate comprising a frame, a supporting-bar pivoted at one end to the frame, a vertically-movable latch-bar pivoted at its lower end to said supporting-bar and in guided connection at its upper end with the frame, a retracting-spring connecting the supporting-bar with the frame, a lever pivoted to the latch-bar, and a latch member pivoted to said lever to engage the latch-post and adapted to be held in connection with the post by the action of the lever to secure the bar in latching position against the action of said spring.

4. In a swinging gate, the combination of hinging and latch posts, a keeper at the lower end of the latch-post, a gate hinged at one end to the hinging-post, a supporting-bar pivoted at one end thereto, a latch-bar at the free end of the gate pivoted adjacent its lower end to said supporting-bar and in guided connection adjacent its upper end with the free end of the gate, locking means at the upper end of the gate to engage the latch-post and hold said latch-bar seated in the keeper, and a retracting-spring connecting the supporting-bar with the frame of the gate and operative to elevate said supporting and latch bars when said locking means is released.

5. A swinging gate comprising a frame provided at its upper free end with a guide, a latch-bar movable in said guide, a supporting-bar pivotally connecting the lower end of the latch-bar with the frame, a contractile spring connecting the free end of the supporting-bar with the frame and adapted to exert its energy to elevate the latch-bar, and means for connecting the upper end of the latch-bar with the gate-post to hold said bar from upward movement.

In testimony whereof I affix my signature in presence of two witnesses.

CHARLES PATTEN.
